UNITED STATES PATENT OFFICE

1,989,392

WINDOW GUARD AND LOCK

Lytle S. Adams, Chicago, Ill., assignor to Charles K. Ernst, Buffalo, N. Y.

Application February 16, 1933, Serial No. 657,096

34 Claims. (Cl. 20—71)

The present invention relates to window closures and the like, and attempts to overcome the trouble experienced with the general type now used. It has been comparatively easy to gain entrée to a building due to the frail and flimsy closures that have been used. In addition, screens that are now being used are, as a rule, so weakly attached that they can be pushed out with little exertion. As a result, there have been numerous kidnappings, petty thievery, and numerous instances of small children falling out of the window because of these weakly constructed closures and poorly attached screens.

An important object of my device is to prevent children from falling out of the windows of dwellings where only a screen is used to prevent such happenings, by securely attaching the screens to a window barrier.

Another object of this invention is to secure the barrier and screen to the upper sash of the window. This type of a barrier would be most applicable in institutions where a great deal of difficulty is experienced in preventing patients from escaping through the windows.

Still another object of this invention is to prevent the removal of the barrier and the screen from the inside or out without the use of a key to operate the lock which secures the unit to the window.

A still further object of my invention is to permit the upper sash to be lowered to a perceptible degree without removing the barrier frame.

A still further object of my invention is to provide means for completely covering the locking construction so as to render it difficult to be manipulated without the use of a key.

Another object of my invention is to provide the grille frame out of a blank which is bent upon itself to form a rectangular frame for the openwork grille and to securely lock the grille to the frame.

It is also an object of the invention to provide a barrier of the above indicated character, which is simple and substantial in construction, which can be manufactured economically and which will be thoroughly efficient and practical in use.

With these and various other objects in view, the invention may consist of certain novel features of construction and operation as will be more fully described and particularly pointed out in the specification, drawings and claims appended hereto.

In the drawings, which illustrate an embodi-

ment of the device and wherein like reference characters are used to designate the parts.—

Fig. 1 is an exterior view of the window frame showing my improved barrier and screen attached thereto, with the upper sash lowered; 5

Fig. 2 is a partial sectional view taken on the line 2—2 of Fig. 1 with the barrier and screen shown in elevation;

Fig. 3 is a fragmentary sectional view showing the lug guide attached to the upper window sash 10 and its relation to the barrier and barrier lug;

Fig. 4 is a sectional view showing the manner in which the barrier unit is secured and locked to the sill of the window;

Fig. 5 is a vertical sectional view taken on 15 line 5—5 of Fig. 4;

Fig. 6 is an elevation of the barrier frame and its locking means with the openwork grille attached thereto;

Fig. 7 is a modification of the locking means as 20 shown in Fig. 5.

Fig. 8 is a fragmentary perspective of a top corner showing the means for attaching the guide lug to the barrier frame.

Fig. 9 is a fragmentary perspective showing 25 the manner in which the bottom corners of the barrier frame are formed;

Fig. 10 is a further modification of the locking means; and

Fig. 11 is a fragmentary sectional view showing 30 the manner in which the grille is attached to the barrier frame.

Referring to the drawings, the numeral 10 indicates the window frame having an upper sash 12 and a lower sash 14. The barrier frame 35 16 is provided with open grille work 18 and has integrally secured thereto a screen 20.

The top edge of the frame 16 is provided with two inwardly extending lugs 22 which are slotted at 24 and adapted to slidably engage the guides 40 26 which are secured to the upper sash 12, as will be later described.

In order to attach the upper guide 26 to the upper sash 12, threaded bolts 28 are inserted through the openings 30 in the flanged portion 45 of the guide 26, and then through the smaller openings 32 in the upper sash 12 and has secured to its ends, a washer 34 which is flattened in order to prevent the bolt 32 from being unscrewed. The large opening 36 in the upper sash 12 is then 50 filled with cement 38 flush to the inside of the window and sash 12. The flanged lower portion 40 is attached to the lower end of the window sash 12 in any well known manner, as at 41.

Attached to the bottom and center of the bar- 55

rier frame 16 is a lug 42 which is secured to the sill in the following manner. A casing 44 is inserted into the opening 46 of the window sill and any well known lock 48 having a retractable bifurcated member 50 is then securely attached to the casing (not shown). A plate 52 having vertical spacing members which rest upon the top of the casing 44 is then secured to the casing 44 as at 56. A cover plate 58 is then placed over the parts and secured to the window sill as at 60. The barrier and screen unit are then swung into place, the aperture in the lug 42 being directly over the aperture 62 in the cover plate. A threaded bolt 64 having a reduced portion 66 is then inserted into the lug and cover plate apertures and threaded in the aperture 68 in the plate 52 until the lug 42 is clamped securely. The key 70 is then turned to operate the bifurcated member 50 which engages the reduced portion 66 and prevents the unthreading of the bolt.

Referring to Figure 3, I have provided a closure strip 71, which is attached along the bottom of the upper sash 12 and between the guides 26 so as to prevent moisture or dust falling through the space between the upper sash 12 and the barrier frame 16 and screen 20.

The barrier frame 16 consists of a U-shaped channel of steel or other suitable metal, the sides 30 of which are so notched at suitable intervals that the channel may be bent to form a rectangle.

The bitter ends 29' and 29'' meet at the point 29 and are joined by inserting a suitable spacer 31 and securing the same in any well known manner as by rivets 33 or by spot welding.

In Figure 6, I have illustrated the manner in which the grille 18 may be attached to the barrier frame 16. Since the extreme outside dimension of the grille coincides with the inside dimension of the barrier frame, the grille is held immovable within the frame when the open end is closed.

Referring to Figure 11, the channel is then compressed by means of any suitable tool so that the sides of the channel meet at the point 13. In order to provide additional security the point 13 may be riveted or spot welded.

In Figure 8, I have shown the manner in which the guide lug is attached to the barrier frame 50 which consist in inserting the guide lug 22 into an opening 23 in the barrier frame 16. A spacer 25, of approximately the same area as the guide lug 22, is then inserted and then the spacer 25 and the lug 22 are secured to the walls of the 55 channel in any well known manner as by rivets 27 or by spot welding.

In Figure 7 I have shown a modification of the locking means which consists of a casing 72 which is secured to the window sill as at 74 and adapted to receive the threaded bolt 76. The bolt 76 is bored to receive the locking member 78 operable by the key 80. When the key is turned the lugs 82 move in the opening 84 and engage the under surface of the casing 72 and prevent the removal of the threaded bolt 76. The lug 84 is adapted to be secured to the sill by the nut 86 of the bolt 76 and is similar to the lug 42 shown in the preferred form except that it functions as a cover plate as well and completely 70 covers the locking parts.

In Figure 10 I have shown another modification of the locking means which consists of a casing 45 which is secured to the sill (not shown) and adapted to receive a lock 58 which is secured to the casing (not shown).

I have shown a plate 53 having vertical spacing members which is similar to plate 52 in my preferred form and is secured to the casing 45 and the window as at 55.

The retractable bifurcated member 50 is adapted to engage the reduced portion 88 of a bolt 90. The bolt 90 is securely attached to the bottom of the barrier frame 16.

I have provided a cover plate 58 which is attached to the sill as at 60 and has a cut out 10 portion 59 which allows the bolt 90 to drop into position and become locked by the member 50.

I have also provided another cover plate 57 which is likewise attached to the barrier frame and adapted, when the frame is swung into position, to completely cover all the locking parts from view in the front.

I claim:—

1. In a device of the character described, the combination of a frame, an upper and a lower movable member mounted therein, a grille unit including a guarded reticulated member movably mounted on said upper movable member and latching means for securing said grille unit to said frame. 25

2. In a device of the character described, the combination of a frame, an upper and a lower movable member mounted therein, and a grille unit including a guarded reticulated member movably mounted on said upper movable member. 30

3. In a device of the character described, the combination of a frame, an upper and a lower movable member mounted therein, and a grille unit including a guarded reticulated member mounted on said upper movable member. 35

4. A grille unit including a guarded reticulated member movably mounted on the upper of two movable members and latching means for securing said grille unit to the frame for the two movable members, said latching means including a cover plate carried by said grille unit and having cooperative relation to said frame, and cooperating locking means on said frame and grille unit. 40

5. A grille unit including a guarded reticulated member movably mounted on the upper of two movable members and latching means for securing said grille unit to the frame for the two movable members, said latching means including a cover plate carried by said grille unit and having cooperative relation to said frame, a cooperating locking means on said frame and grille unit and disposed behind said cover plate. 45

6. In a device of the character described, the combination of a frame, an upper and a lower transparent member slidably mounted therein and a grille unit including a guarded reticulated member movably mounted on said upper transparent member. 55

7. In a device of the character described, the combination of a frame, upper and lower transparent members slidably mounted therein and a grille unit including a guarded reticulated member movably mounted on said upper transparent member, and latching means for securing said grille unit to said frame. 65

8. In a device of the character described, the combination of a frame, upper and lower transparent members slidably mounted therein and a grille unit including a guarded reticulated member movably mounted on said upper transparent member, and latching means for securing said grille unit to said frame, said latching means including a cover plate carried by said grille unit 70

and having cooperating relation to said frame, and a cooperating latching means on said frame and grille unit.

9. In a device of the character described, the combination of a frame, an upper and a lower opaque member slidably mounted therein and a grille unit including a guarded reticulated member movably mounted on said upper opaque member.

10. 10. In a device of the character described, the combination of a frame, an upper and a lower opaque member slidably mounted therein and a grille unit including a guarded reticulated member movably mounted on said upper opaque member and latching means for securing said grille unit to said frame.

11. In a device of the character described, the combination of a frame, an upper and a lower opaque member slidably mounted therein and a grille unit including a guarded reticulated member movably mounted on said upper opaque member and latching means for securing said grille unit to said frame, said latching means including a cover plate carried by said grille unit and having cooperative relation to said frame, and cooperating locking means on said frame and grille unit.

12. In a device of the character described, the combination of a frame, an upper and a lower movable member mounted therein, a grille unit including a guarded reticulated member movably mounted on said upper movable member and a guard disposed between said upper movable member and grille unit to prevent passage of extraneous matter therebetween.

13. A grille unit including a guarded reticulated member movably mounted on the upper of two movable members and latching means for securing said grille unit to the frame for the two movable members and a relatively movable member on said grille unit, a lock on said frame having a retractable bifurcated member adapted to have cooperative relation to said relatively movable member for selectively preventing movement of said grille unit.

14. A grille unit including a guarded reticulated member movably mounted on the upper of two movable members and latching means for securing said grille unit to the frame for the two movable members, a relatively movable member on said grille unit, a lock on said frame having a retractable member adapted to have cooperative relation to said relatively movable member for selectively preventing movement of said grille unit.

15. In combination with the upper window sash of a barrier frame constructed of open work having means for engaging said upper window sash, said engaging means comprising inwardly extending lugs at the top of said barrier frame adapted to engage retaining means, and a sill engaging means comprising an inwardly extending lug adapted to engage locking means on said sill, said top engaging means adapted to slidably engage the retaining means on the upper window sash, said retaining means comprising a guide having inwardly extending flanges adapted to be engaged by connecting means, said connecting means being secured to the upper sash, said barrier frame having a screen attached thereto.

16. In combination with the upper window sash of a barrier frame constructed of open work and a screen attached to said barrier frame, means for allowing movement of the upper sash, said

means comprising a vertical guide having inwardly extending ends adapted to engage connecting means in said upper sash and secured thereto, said guide adapted to be engaged by an inwardly extending lug on said barrier frame, said guide securing means comprising a bolt and a washer attached to the bolt on its outer end, said end and outer washers cemented to said upper window sash.

17. In combination with the upper window sash of a barrier frame constructed of open work having means for engaging said upper window sash, said engaging means comprising inwardly extending lugs at the top of said barrier frame adapted to engage retaining means, and a sill engaging means comprising an inwardly extending lug adapted to engage locking means on said sill, said top engaging means adapted to slidably engage the retaining means on the upper window sash, said retaining means comprising a guide having inwardly extending flanges adapted to be engaged by connecting means, said connecting means including a plurality of bolts, the outer ends of which are attached to the upper of said inwardly extending flanges and the inner ends adapted to be inserted into the small openings in the upper sash, said inner ends provided with washers permanently affixed thereto and adapted to be secured into the large opening in the upper window sash in any well-known manner as by cementing.

18. In a device of the character described, the combination of a frame, an upper and lower movable member mounted therein, a grille unit including a guarded reticulated member pivotally and slidably mounted on said upper movable member.

19. In a device of the character described, the combination of a frame, an upper and lower transparent member slidably mounted therein and a grille unit including a guarded reticulated member mounted on said upper transparent member, and latching means for securing said grille unit to said frame, said latching means including a cover plate carried by said grille unit and having cooperative relation to said frame, and cooperative latching means on said frame and grille unit and disposed substantially to the rear of said cover plate.

20. In a device of the character described, the combination of a frame, an upper and lower opaque member slidably mounted therein and a grille unit including a guarded reticulated member mounted on said upper opaque member, and latching means for securing said grille unit to said frame, said latching means including a cover plate carried by said grille unit and having cooperative relation to said frame, and cooperative latching means on said frame and grille unit and disposed substantially to the rear of said cover plate.

21. In a device of the character described, the combination of a frame, an upper and lower transparent member mounted therein, a grille unit including a guarded reticulated member movably mounted on said upper transparent member and a guard disposed between said lower transparent member and grille unit to prevent passage of extraneous matter therebetween.

22. In combination with an upper window sash of a barrier frame constructed of open work and a screen attached to said barrier frame, means for allowing movement of the upper sash, said means comprising a guide engaging means located on said barrier frame, said guide integrally attached to the upper sash.

23. In combination with an upper window sash of a barrier frame constructed of open work and a screen attached to said barrier frame, means for allowing movement of the upper sash, said means comprising a vertical guide engaging means located on said barrier frame, said guide integrally attached to the upper sash. 5
24. In combination with an upper window sash of a barrier frame constructed of open work and a screen attached to said barrier frame, means for allowing movement of the upper sash, said means comprising a vertical guide having inwardly extending ends adapted to engage connecting means in said upper sash and secured thereto, said guide adapted to be engaged by an inwardly extending lug on said barrier frame. 10
25. In combination with a window of a barrier frame and screen, said frame and screen slidably secured to the upper sash of a window and rigidly secured to the sill of a window. 15
26. In combination with a window of a barrier frame and screen, said frame and screen slidably secured to the upper sash of a window and rigidly secured to the sill of a window, securing means on said upper sash comprising slide members anchored on the outer side of said sash. 20
27. In combination with a window of a barrier frame and screen, said frame and screen slidably secured to the upper sash of a window and rigidly secured to the sill of a window, said barrier member having lugs on its upper corners and said upper sash having members cooperating with said lugs to permit vertical movement of said barrier. 25
28. In combination with a window sill and the upper sash of a window, of a barrier frame and a window screen secured thereto, said barrier frame rigidly secured to said sill and movably secured to said upper sash. 30
29. In combination with a window sill and the upper sash of a window of a barrier frame and a window screen secured thereto, said barrier frame rigidly secured to said sill, and movable sill securing means, said sill securing means consisting of a lock, a lock cover plate, securing means for said lock cover plate, a barrier frame lock engaging means, and a cover plate for said engaging means. 35
30. In a combination with a window sill and the upper sash of a window of a barrier frame and a window screen secured thereto, said barrier frame rigidly secured to said sill, and movable sill securing means, said sill securing means consist- 40
- ing of a lock, a lock cover plate, securing means for said lock cover plate, a barrier frame lock engaging means, said engaging means consisting of a downwardly extending lug adapted to be engaged by said lock. 45
31. In combination with a window sill and the upper sash of a window, of a barrier frame and a window screen secured thereto, said barrier frame rigidly secured to said sill, and movable sill securing means, and means for obliterating said securing means. 50
32. In combination with a window sill and the upper sash of a window, of a barrier frame and a window screen secured thereto, said barrier frame rigidly secured to said sill, and movable sill securing means, means for obliterating said securing means, said obliterating means consisting of a cover plate rigidly secured to said barrier frame and adapted to conceal the securing means from the outside. 55
33. In combination with a window sill and the upper sash of a window of a barrier frame and a window screen secured thereto, said barrier frame rigidly secured to said sill, and movable sill securing means, said securing means including an inwardly extending lug integrally secured to the bottom and center of said barrier frame, and apertured to receive the head of a threaded bolt, said bolt so positioned as to also pass through the aperture in the cover plate for a lock unit, said lock unit provided with a spacing member adapted to threadingly engage said bolt, said threaded bolt provided with a reduced portion having cooperative engagement with a bifurcated retractable member operated by a lock, said bifurcated retractable member adapted to prevent removal of said bolt from said lock unit. 60
34. A grille unit including a guarded reticulated member movably mounted on the upper of two movable members and latching means for securing said grille unit to the frame for the two movable members, said latching means including a cover plate carried by said grille unit and having cooperative relation to said frame, and cooperating locking means on said frame and grille unit, said locking means including a downwardly extending lug having a reduced portion having cooperative relation with a retractable bifurcated member operated by a lock and adapted to prevent the removal of said downwardly extending lug. 65

LYTLE S. ADAMS.
